FILING DRAWER

Ernest Rose, Washington, D. C., assignor to International Business Machines Corporation, New York, N. Y., a corporation of New York

Application June 4, 1935, Serial No. 24,813

5 Claims. (Cl. 129—16)

This invention relates to filing cabinets in general.

The broad object of the invention is to provide a filing cabinet in which records are kept flat under pressure to prevent them from curling and buckling.

An object is to provide a filing cabinet which is especially suitable for filing records such as accounting and statistical punched cards like the ones used in the well known Hollerith system. It is necessary that such cards be kept flat when not in use to prevent them from curling as much as possible. Otherwise, trouble will be experienced when the cards pass through the machine as curled or buckled cards have a tendency to jam in passing through the machine or are not likely to be fed by the usual card picker mechanism.

Another object is to provide an improved drawer construction for filing cabinets.

An object is to provide a novel means whereby the operation of closing the drawer of a filing cabinet causes pressure to be applied to the records in the drawer for the purpose of preserving the flat condition of the records filed in such drawer and whereby the opening of the drawer automatically relieves the pressure on the records to permit removal of as many as desired.

Various other objects, advantages, and features of the present invention will be specifically explained in the following description and claims or will be readily perceived from a study of the description, claims and drawing.

The single figure of the drawing illustrates a plan view of a filing cabinet drawer embodying the invention.

The drawing illustrates in plan view a sheet metal filing cabinet drawer of conventional construction comprising sides 1, front 2, back 3, and bottom 4. The specific material of which these parts are composed, the means for securing them together, and their specific shape are not important and form no part of the present invention. The bottom 4 of the drawer is formed with a channel 5 and in this channel, supported by the front 2 and back 3, is a rod 6. The channel 5 and rod 6 cooperate to guide a vertical backing or follower plate 7 of conventional form through which the rod 6 passes. The follower plate 7 has the usual finger piece 8 which forms part of the usual clamp cooperating with the rod 6 or the walls of channel 5 to hold the follower plate 7 in any desired position along rod 6. The plate 7 has a finger piece 9 formed therein

so that the clamp may be released to adjust the plate 7 by merely pinching together both finger pieces 8, 9. However, any other form of clamping means or means for adjusting or guiding the plate 7 may be used as a large number of different forms are known in the art.

A pressure or compressor plate 10 rests edge-wise on the bottom 4 and is resiliently attached to a third or operating plate 11 also resting on the bottom 4. The means by which the plate 10 is resiliently attached to plate 11 consists of a plurality of headed pins 12, which loosely pass through holes in plate 11 and are riveted to pressure plate 10, and compression springs 13 which surround the pins 12 between the plates 10, 11 and tend to force the plates away from each other, movement being limited, however, by the heads of pins 12. Preferably, at least two rows of pins 12 and their springs 13 are provided and are arranged near the upper and lower edges, respectively, of the plates 10, 11 in order to equalize as much as possible the pressure applied by the plate 10 to the cards 14 or other records filed between follower plate 7 and pressure plate 10.

Preferably, one or both of the plates 10, 11 has a tab formed in or secured thereto through which the rods 6 passes to prevent the plates 10, 11 from being removed. In some filing cabinets the rod 6 is absent and the follower plate 7 is guided by some such expedient as a channel or rib formed in the sides 1 or secured thereto. In such constructions the channel or rib may have a similar function for one or both of plates 10, 11. The means by which plates 7, 10, 11 are guided is not a feature of the present invention and the only requirements to be satisfied are that the plates 10, 11 shall be free to move a limited amount lengthwise of the drawer and that preferably plate 7 be adjustable.

Plate 11 is movably connected to the drawer front 2 by means of a pair of toggles comprising links 15. These toggles are pivoted at their rear ends to plate 11 at points about half-way between the top and bottom edges of said plate and equal distances from the ends. The front ends of the toggles are pivotally connected to the inside of the drawer front 2 at points directly opposite the points at which the toggles are pivoted to plate 11. In other words, the lines of action of the toggles are parallel with the longitudinal axis of the drawer and intersect plate 11 at points half-way between the longer edges thereof. This relation is desirable in order that

the plate 10 exert an even pressure on cards 14 placed behind said plate and in front of plate 7.

Adjacent each toggle there is a spring 16 attached to the drawer front 2 and plate 11 so as to have a tendency to draw plate 11 toward the drawer front 2. The lines of action of these springs and the lines of action of the toggles are parallel and in the same horizontal plane.

Each toggle is provided with an anti-friction roller 17 which is rotatably mounted on the screw or rivet by means of which the links 15 are pivoted together. These rollers bear on a U-shaped member 18, the legs of which are slidably mounted in the holes in the drawer front 2. The drawer pull 19 is secured to the front ends of the member 18 by any suitable means as screws 20.

When the drawer is closed, the parts have the position shown in the drawing in which it will be noted that the springs 13 are partly compressed to exert a pressure on plate 10. This pressure is communicated by plate 10 to the cards 14, thereby forcing them back against the follower plate 7. This pressure keeps the cards flat and prevents the buckling or curling from heat or moisture which would be likely to take place if the cards were loose and free to bend as is usually the case when they are loosely stored in ordinary filing cabinets.

30 When the handle is grasped and the drawer pulled out, the U-shaped member is drawn forwardly relative to the front 2 with the result that the toggles will bend under the influence of springs 16 permitting said springs to draw plates 10, 11 away from the cards 14 and toward the drawer front 2. The parts are so designed that when the drawer handle is pulled as far forward as it will go, plate 10 will be withdrawn far enough to enable the separation of the cards by hand sufficiently to remove all or any portion of them.

Before the drawer is closed after the insertion or removal of cards, the follower plate is positioned so that there is little or no looseness in the cards.

45 When the drawer is closed, the pressure of the hand on the drawer pull 19 forces member 18 inwardly back to the position shown in the drawing thereby camming the rollers 17 toward the sides 1 and partly straightening the toggles. This causes plates 10, 11 to move toward the cards to compress them into a flat condition which is maintained, as long as the drawer is closed by virtue of the resiliency of springs 13.

50 The construction described above was designed primarily for use in cabinets in which are filed the perforated accounting and statistical record cards commonly employed in the Hollerith and other perforated record controlled machines. 60 However, this construction or modifications of it may be used in filing cabinets for other things, photographs and photographic negatives, for example, which are considerably more likely to curl or buckle from the effects of age, temperature, and moisture.

70 While there has been shown and described and pointed out the fundamental novel features of the invention as applied to a single embodiment, it will be understood that various omissions and substitutions and changes in the form and details of the device illustrated and in its operation may be made by those skilled in the art without departing from the spirit of the invention. It is the intention therefore to be limited

only as indicated by the scope of the following claims.

What is claimed is as follows:

1. In a filing cabinet drawer, a follower plate adjustable relative to the front of the drawer, a compressor plate movable toward and away from the follower plate between which compressor plate and follower plate the papers to be filed may be placed, a second plate interposed between the front of the drawer and the compressor plate and movable toward the compressor plate and follower plate, resilient means connecting the second plate and compressor plate whereby the latter may yield relative to the second plate when the second plate is moved toward the follower plate whereby to apply a uniform pressure to the papers between the compressor plate and follower plate, a drawer pull slidably mounted in the drawer front and movable toward and away from the follower plate, a pair of toggles interconnecting the front of the drawer with the second plate, resilient means tending to break the toggles and draw the second plate and compressor plate toward the front of the drawer to release papers compressed between the follower plate and compressor plate, said toggles engaged in the drawer pull whereby movement of the drawer pull inwardly toward the drawer front causes the toggles to be straightened to actuate the second plate toward the compressor plate. 30

2. In a filing cabinet drawer, backing means for papers to be filed, a pressure plate movable toward the backing means to apply pressure to papers between the backing means and pressure plate, a second plate spaced from the pressure plate and parallel with the latter, means to limit relative movement of the pressure plate with respect to the second plate in the direction of the backing means, resilient means for causing said relative movement, a drawer pull movably 40 mounted on the front of the draw, and toggle means engaged with said drawer pull for operating the second plate.

3. In a filing cabinet draw, an operating plate movable toward and away from the rear face 45 of the front of the drawer and a drawer pull movably mounted on the front face of the drawer front and extending into the space between the drawer front and operating plate, resilient means tending to move the operating plate toward the 50 drawer front, means engaging said drawer pull for moving the operating plate rearwardly of the drawer front against the tension of the resilient means when the drawer pull is operated to close the drawer, a pressure plate mounted on the 55 rear face of the operating plate, means to limit relative movement of the pressure plate rearwardly of the operating plate, and yielding means interposed between said plates to cause the operating plate to move relative to the pressure plate.

4. In a filing cabinet drawer, backing means in front of which the papers to be filed are placed, a pair of movable plates located between the backing means and the front of the drawer and movable as a unit toward and away from said backing means, the papers to be filed being placed between one of the movable plates and the backing means, resilient means for mounting one of the movable plates on the other whereby the movable plate nearest the front of the drawer is permitted to move a limited amount toward the other movable plate when the latter is obstructed by papers in front of the backing means to apply pressure to said papers to hold them in flat con- 70

dition, a drawer pull movably mounted on the front of the drawer, and means engaging said drawer pull for moving the movable plates when the drawer pull is moved relative to the drawer.

5 5. In a filing container of the class described, a backing plate, a pressure plate between which and the backing plate records to be filed are placed, and an operating plate, said pressure plate and operating plate being spaced from each other 10 and parallel with the backing plate and mounted for movement toward and away from the backing plate, means resiliently mounting the pressure plate on the face of the operating plate nearest the backing plate whereby the operating plate 15 may be moved a further distance toward the back-

ing plate and pressure plate when the movement of the latter is obstructed by records in front of the backing plate whereby to apply pressure to said records to hold them in flat condition, an operating handle, said container including a 5 fixed support for said handle said operating handle being movably mounted on said support, means to move the pressure plate and operating plate as a unit away from the records in front of the backing plate to permit removal of said 10 records, and means actuated by movement of said handle for moving said operating plate and pressure plate toward said records.
